PERCUSSIVE UNIT FOR EARTH DRILLING
James M. Cleary, Dallas, Tex., assignor to The Atlantic Refining Company, Philadelphia, Pa., a corporation of Pennsylvania

Filed Dec. 6, 1965, Ser. No. 511,870
29 Claims. (Cl. 173—137)

This is a continuation-in-part of application Serial No. 241,412, filed November 30, 1962, now Patent No. 3,229,775.

This invention is concerned with fluid-actuated, percussive units for earth borehole drilling.

Fluid-actuated earth drilling percussive units are commonly composed of an elongated tubular housing having a power fluid inlet and outlet, a valving and passage system for controlling passage of the power fluid through the power unit, and a power chamber. Slidably mounted in the power chamber is a piston-like hammer which is adapted to reciprocate up and down to impact an anvil to which a drill bit is attached. Usually, the anvil is splined or grooved to cooperate with grooves or splines in the lower portion of the housing so that the drill bit and anvil are rotated by rotation of the housing. Such percussive devices are rotated so that the cutting elements of the drill bit are indexed to a new position between hammer blows. Longitudinal reciprocal movement of the hammer is accomplished by alternately applying power fluid to the ends of the hammer. When power fluid is applied to the lower end of the hammer between the anvil and hammer, the hammer is accelerated in an upward direction until entry of the power fluid no longer acts on the lower end of the hammer. The upward energy of the hammer is then transmitted to an elastic rebound cushion. This rebound cushion is usually either a trapped volume of compressible power fluid, or a hammer return spring, or both. The hammer continues moving upward until the velocity of the hammer is zero and the direction of movement of the hammer is reversed. Before or at the peak of the upstroke of the hammer, the valving system switches flow of high pressure power fluid to the upper end of the hammer. When the hammer starts to move downward, part of the energy stored in the elastic rebound cushion is returned to the hammer. This energy combines with energy developed by the power fluid to accelerate the hammer downward to impact the anvil. This downward percussive force is transmitted to the drill bit and drives the cutting elements of the drill axially into the earth formation.

The ultimate objective in percussive tool design is to provide a durable gas- or liquid-operated tool exhibiting both a high energy, high frequency impact and a high fluid conductivity per unit diameter over a wide range of operating conditions. The achievement of this ultimate objective depends primarily on the stability, reliability and uniformity of the timing relationship between the up and down movement of the hammer and the instants that the valving system ceases and starts the flow of power fluid to alternate ends of the hammer. This timing relationship affects and is affected by almost every operating feature of the percussive unit; however, it has been found that many of the problems involved in interrelating all of the tool's features to achieve the ultimate objective are overcome by providing a valving arrangement exhibiting better cooperation between the hammer and valve and by providing better spring means above the hammer for reversing the upward movement of the hammer into its downward or power stroke.

Accordingly, it is an object of this invention to provide a valving system that increases the horsepower output per unit energy input and per unit tool diameter, permits

2

the use of both compressible and incompressible power fluids, increases the conductivity to fluid flow of the power unit, provides more reliable and uniform operation and cooperative relation between the hammer and valve, causes the power fluid to act on the hammer throughout the power stroke, permits the power unit to operate efficiently over a wider range of operating conditions, reduces friction and failures, or exhibits great flexibility of adjustment or timing to different percussive tool components and other operating conditions.

It is a further object of this invention to provide an overhead spring for use during the period when the hammer reverses direction of movement and that allows the valve and hammer to operate more efficiently together while reducing wear of the cooperating parts. This overhead spring provides smoother uniform movement of the hammer and valve, increases timing reliability and stability, causes the full power fluid pressure differential to act on the hammer to the moment of impact, permits greater power unit fluid conductivity, allows the use of both incompressible and compressible power fluids, increases the operating range of the power unit with more efficient horsepower output per unit energy input per unit tool diameter, or is suitable for prolonged and rapid receipt, storage, and release of energy to and from the hammer.

Yet another object is to provide a system that facilitates removal of impurities or other contaminants from the incoming power fluid.

Other advantages and objects of this invention will become apparent by reference to the accompanying drawings, appended claims and following specification.

In the drawings:

FIGURE 20 is a cam layout for the cam of FIGURES 18 and 19.

FIGURE 21 is a schematic depicting a hammer and valve cycle.

FIGURES 22, 23 and 24 are an elevational cross-sectional, a top cross-sectional and a bottom end view, respectively, of one of the rod springs of FIGURE 18.

First, this invention concerns a ported, rotatable tubular valve combined with motion conversion means adapted to employ the reciprocating or longitudinal movement of a hammer to coordinate the axial motion and position of the hammer with the circumferential rotative position of power fluid inlet and exhaust ports in the valve during at least a portion of the reciprocating cycle of the hammer. This motion conversion means may be a cam and follower arrangement. The operation of the rotatable valve is vastly improved if the tubular valve has at least two inlet ports and at least two exhaust ports which are spaced substantially symmetrically around the circumference of the valve, thereby balancing fluid pressures exerted on the valve. In one embodiment, the valve is connected to a rotary drive means which rotates the valve at a speed of rotation greater than the speed of rotation of the percussive unit and drill bit. When the rotary drive means is present, the cam may be a single- or double-acting cam. In a second embodiment, the cam is adapted to rotate the valve and a separate rotary drive means is not required. One means for accomplishing this is to make the cam a double-acting cam.

Secondly, this invention concerns a novel elongated, rod-like spring member positioned above a hammer of a percussive unit. The rod-like spring member is at least twelve times as long as its average effective width with its longitudinal axis substantially parallel to the longitudinal axis of the casing and having a lower end positioned to squarely or axially contact an upper surface of the hammer. The spring receives energy from the hammer during a last portion of the hammer's upstroke and returns a portion of this energy during a first part of the downstroke or power stroke of the hammer. Preferably, this rod-like spring is combined with the rotatable valve and is restrained against buckling.

Thirdly, this invention relates to a percussive unit embodying some or all of the above and other elements of this invention. Other elements of this invention not mentioned previously are the employment of a spring above the hammer having a spring rate of at least five thousand pounds per inch, and the placement of a contaminant removal means or by-pass separator inside the rotatable tubular valve.

The word rotatable as used herein in relation to the tubular valve includes a tubular valve that rotates back and forth in an arc of one revolution or less as well as one that rotates in only one direction.

More specifically, in FIGURES 1 and 2, there is shown one embodiment of a percussive unit built in accordance with the present invention. The percussive unit includes tubular housing 11 whose upper end is removably connected to a rotary drill string (not shown) which conducts power fluid to the percussive unit.

slidably telescoping into the lower end of housing 11 is anvil 13 having an upper anvil surface and which is capable of limited longitudinal movement within the housing. Longitudinally traversing the anvil is central anvil bore passage 15 whose lower end (not shown) communicates in the usual fashion with fluid discharge passages in a drill bit. In the usual manner, the anvil is designed to rotate with housing 11.

In housing 11 above anvil 13 is piston-like hammer 17 which is slidably mounted within housing 11 to undergo reciprocal, longitudinal, or up and down movement and periodically impact anvil 13. The hammer has upper surface 19 and lower surface 21. In the illustrated embodiment the lower portion of hammer 17 is of smaller diameter than the upper portion, thereby forming shoulder

23 at a point intermediate of the ends of the hammer.

As shown in FIGURES 1 and 4 through 7, longitudinally traversing hammer 17 is central bore 25. Communicating with this central bore passage is at least one upper or first hammer passage 27 which also communicates with the upper surface or end of the hammer and the interior of housing 11 above the hammer. As shown, first hammer passages 27 are two vertical grooves leading to the top of the hammer which are spaced 180 degrees on center and substantially symmetrically around the circumference of central bore 25. These passages extend deep enough into the bore of the hammer to communicate with ports in a rotatable valve and, during operation of the percussive unit, these first hammer passages conduct power fluid to and from the cylinder chamber above the hammer as hereafter set forth.

Also communicating with the central bore passage in the hammer is at least one lower or second hammer passage 29 which in turn communicates with the lower surface or end of the hammer by way of shoulder 23. As shown, second hammer passages 29 include a groove in the wall of the central bore of the hammer, two bores which pass through the walls of the hammer and two vertical grooves in the outer surface of the hammer. These passages are spaced 180 degrees on center and substantially symmetrically around the circumference of central bore 25. These passages are also spaced 90 degrees on center from first hammer passages 27. Second hammer passages 29 are located in the hammer bore to communicate with ports in a rotatable valve and, during operation of the percussive unit, these second hammer passages conduct power fluid to and from the lower end of the hammer as hereafter set forth.

Extending longitudinally through the central bore in hammer 17 and into the central bore of the anvil is a rotatable tubular valve 31 which, as illustrated, has a central passage which is open at its lower end and which near its upper end has inlet openings 33. The tubular valve is free to rotate substantially independently of housing 11 and the anvil and bit.

Near the top of the housing and tubular valve is rotary drive means 35 which is connected to or made a part of tubular valve 31. The rotary drive means will be hereafter described in more detail.

Below rotary drive means 35 and inlet openings 33 in tubular valve 31 is at least one first port through the wall of the tubular valve which port or ports form power fluid inlet ports 37 which, when the drill bit is on bottom and the valve is rotated, alternately communicate with the first and second hammer passages to conduct power fluid to above and below the hammer. Preferably, for reasons herein made apparent, there will be at least two inlet ports in the tubular valve and the ports will be spaced substantially symmetrically around and through the circumference of the tubular valve as shown in FIGURES 1, and 8 through 10, wherein there are two such inlet ports which are 180 degrees on center.

As shown in FIGURES 1 and 8 through 10, through the wall of the tubular valve is at least one second port which port or ports form power fluid exhaust ports 39, which, when the drill bit is on bottom and the valve is rotated, alternately communicate with the first and second hammer passages to conduct power fluid from above and below the hammer. Preferably, for reasons herein made apparent, there will be at least two such exhaust ports and the number of exhaust ports will equal the number of inlet ports 37. These exhaust ports will be spaced substantially symmetrically around and through the circumference of the tubular valve. As shown, there are two such exhaust ports which are 180 degrees on center and are spaced 90 degrees on center from each inlet port.

In tubular valve 31 separating power fluid inlet ports 37 from fluid exhaust ports 39 is flow restrictive means 41 which effectively divides the central passage through

tubular valve 31 into two sections with the section above the flow restrictive means being a power fluid inlet section and the section below the flow restrictor being a power fluid exhaust section. For illustrative purposes only, the wall of the valve and flow restrictor is equipped with grooves that give greater vertical length to inlet ports 37 and exhaust ports 39.

Flow restrictive means 41 has bleed passage 43 which provides greater control of the conductivity of the percussive unit and permits power fluid to escape from the power inlet section of the tubular valve to the exhaust section thereby assuring a continuous stream of fluid for cleaning and flushing the drill bit. Bleed passage 43 also provides a way to remove impurities from the incoming power fluid as hereafter described.

As stated previously, through the wall of tubular valve 31 above power fluid inlet ports 37 and below rotary drive means 35 are inlet openings 33 which communicate with power fluid passageway 45 in casing 11 which conduct power fluid from rotary drive means 35 to tubular valve 31.

Circumscribing and supporting tubular valve 31 is bearing 47 which permits easy rotation of the valve. Preferably bearing 47 will be a ball, thrust bearing.

Return now to rotary drive means 35. This rotary drive may be any form of fluid-actuated rotary device or fluid reaction motor connected to and suitable for rotating tubular valve 31 and may or may not be an integral part thereof. As shown in FIGURES 1 and 11, rotary drive means 35 is of the jet type and includes hollow central chamber 49 which communicates with incoming power fluid from a drill string attached to the upper end of housing 11. Extending outward from central chamber 49 are jet passages 51 and 53 which terminate in jet openings 55 and 57.

The top of central chamber 49 forms a rotatable seal with insert 59 in housing 11. Power fluid passing into central chamber 49 passes to jet openings 55 and 57 located on opposite sides of the rotary drive means so that fluid emitting from these jet openings will cause the rotary drive means to rotate.

As described in copending application Serial No. 241,412, the rotary drive means may be equipped with a suitable form of normally closed centrifugally-operated bypass port which is opened to allow some of the power fluid to bypass the rotary drive means when the rotary drive means reaches its desirable operating speed. This makes the tool more conductive and permits better control of the timing of the valve.

As stated previously, bleed passage 43 is also used as a passageway for removing contaminants or impurities from the inlet section of the tubular valve. Since tubular valve 31 is rotated almost independently of the housing and drill bit, the incoming power fluid spins and the heavier contaminants and impurities in the power fluid are collected on the inner walls of the inlet section of the rotating tubular valve. These impurities travel down the inner wall of the tubular valve until they are collected by a contaminant removal means where the impurities pass through bleed port 43 bypassing the hammer chamber. As shown in FIGURES 12 and 13, the contaminant removal means is made up of upper cylinder portion 61 and lower cylinder portion 63 through which power fluid may pass. Lower cylinder portion 63 is of larger diameter than upper cylinder portion 61 and forms a seal with the inner wall of the tubular valve. This in turn forms trough-like annulus 65 which collects impurities traveling down the inner walls of tubular valve 31. Extending through one side of lower cylinder 63 is bleed passage 43 which communicates with trough-like annulus 65 and the exhaust section of the tubular valve below flow restrictive means 41. Impurities collecting in the trough-like annulus travel into bleed passage 43 where the impurities are flushed into the exhaust section of the percussive unit thereby bypassing the hammer chamber.

Above hammer 17, housing 11 provides a chamber for an elastic rebound cushion which, during a last portion of the upward travel of the hammer, receives and stores energy from the hammer causing the hammer to decelerate and which, during a first part of the downstroke of the hammer, returns a portion of the stored energy to the hammer.

Preferably, the elastic rebound cushion is a compression spring. An improved coil-type compression spring is shown in FIGURE 1 wherein the improved coil spring is comprised of first coil spring 67 and second coil spring 69 which are threaded together in a double helix so that the coils of springs 67 and 69 act in parallel vertical alignment, that is, alternate coils of one spring lie just above 15 and below a coil of the other spring and the coils are aligned. This improved double helix type coil spring has fewer turns per individual spring and exhibits a spring coefficient greater than a single coil spring that could be fitted in the available space. The double helix spring is 20 placed in housing 11 above hammer 17 and positioned to contact upper surface 19 during a last portion of the upstroke of the hammer.

An alternate and superior type of compression spring is shown in FIGURES 18 and 22 through 24. This superior spring is comprised of at least one compression rod spring. As shown in FIGURE 18, there are two elongated compression bar or rod-like springs 71 and 73 mounted in housing 11 above hammer 17. These rod-like springs are positioned and adapted to be loaded axially when struck by upper surface 19 of the hammer; consequently, rod-like springs 71 and 73 have lower ends 75 and 77, respectively, which are positioned above the hammer to be squarely contacted and receive energy from the hammer. The sides of each rod-like spring are supported laterally by housing 11 or other support to prevent buckling; consequently, the rod-like springs act only in axial compression. This type of compression spring is more uniformly stressed than a coil spring and operates under much higher fatigue stresses. The length, L, of 30 each rod-like spring must be at least twelve times as great as the average maximum width, W, of the main body of the rod if the rod-like spring is to operate satisfactorily. Much greater length to width ratios are desired. The spring coefficient for the rod-like spring will ordinarily be 35 greater than 10,000 pounds per inch and spring coefficients much greater than this are preferred.

It has been found that the ported, rotatable tubular valve operates much more efficiently if it is combined with motion conversion means adapted to employ the reciprocating or longitudinal movement of the hammer to coordinate the axial motion and position of the hammer with the circumferential or rotative position of the ports in the valve during at least a portion of the reciprocating cycle of the hammer. In other words, the motion conversion means converts longitudinal motion into rotary motion. This motion conversion means may be a cam and follower arrangement with the cam having at least one curved surface adapted to contact the follower during at least a portion of the reciprocating cycle of the hammer. 50 In a cam and follower arrangement, either the cam or the follower may be in contact with or connected to the tubular valve. As illustrated in FIGURES 1 and 14, single-acting cam 79 is embedded in the upper end of hammer 17 surrounding tubular valve 31 so that the cam moves up and down with the hammer. The top of single-acting cam 79 has single-acting cam surface 81 which has the same general form as the relative motion between the valve and hammer. Since the tubular valve illustrated 55 has two power fluid inlet ports and two power fluid exhaust ports spaced symmetrically around the valve, there is a hammer cycle every 180 degrees of rotation of the valve or two cycles per valve revolution; consequently, there are two single-acting cam surfaces of the same shape with each surface covering 180 degrees of the cam cylinder.

Above single-acting cam 79 is a follower means which is a member, such as a pin, roller or second cam surface, adapted to cooperate with longitudinal movement of single-acting cam 79 during at least a portion of the up and down strokes of the hammer by riding on single-acting cam surface 81 whenever the ports in the tubular valve are not in proper position relative to the up or down position of the hammer. Thus, single-acting cam surface 81 will either speed up or slow down tubular valve 31 whenever ports 37 and 39 are out of position relative to the position of the hammer. As shown, the follower means is pin or roller 83 which traverses tubular valve 31 extending outward through follower slot 85. The follower roller extends beyond the wall of the tubular valve by a distance sufficient to allow the follower roller to be vertically aligned with single-acting cam surface 81.

Preferably, either the follower or the cam should be shock mounted to allow either one to slip or give way if there is a malfunction which causes a miss-match between the up and down motion of the hammer and the rotational movement of the tubular valve. This shock mounting helps to prevent failure or breakage of the percussive unit. One method of shock mounting the follower roller 83 is shown in FIGURES 1 and 15 through 17. The follower roller is affixed to cam follower bushing 87 which in turn is connected to cam follower bushing return spring 89. It will be also noted that follower slot 85 is elongated longitudinally along the length of tubular valve 31. In this manner, whenever there is a miss-match between cam and follower, follower roller 83 will slip upward in follower slot 85 causing cam follower bushing 87 to compress cam follower bushing return spring 89 which will return the follower to its original position when the miss-match is corrected or the hammer moves downward out of contact with the follower.

It will be noted that when a single-acting cam is used, it is usually necessary to have a separate means for starting rotation of tubular valve 31. In the embodiment of FIGURE 1, this separate means is rotary drive means 35; however, rotary drive of the valve may be accomplished by positioning the follower to always follow the cam when the tool is in its normal operating position. As illustrated in FIGURES 18 through 20, this is accomplished by double-acting groove cam 91 which is formed in the wall of the central bore of hammer 17'. This groove cam has at least two cooperating curved surfaces. Follower roller 83', traversing tubular valve 31' in a manner similar to follower roller 83, extends between these curved surfaces. A layout for the double-acting groove cam is shown in FIGURE 20. It will be noted that the lower surface of the groove cam is similar to single-acting cam surface 81. The upper side or surface of double-acting groove cam 91 can have any shape so long as this upper surface properly orients the follower to a starting position whenever the bit is off bottom. As shown, the upper surface is similar to the lower surface except that the upper surface has been cut out to allow the follower free movement at points of turn around of the hammer. At the upper point of the groove cam is upper groove 93. Upper groove 93 communicates with the double-acting cam groove and extends upward. This upper groove allows the hammer to drop whenever the anvil drops below its normal operating position. In other words, when the bit is off bottom, the follower rides up into upper groove 93 allowing the hammer to drop. As will be explained, this provides a way of stopping reciprocation of the hammer.

Consider now the operation of the percussive unit of FIGURE 1. First, note that tubular valve 31 is rotated thereby rotating power fluid inlet ports 37 and power fluid exhaust ports 39. As shown, there are two inlet ports and two exhaust ports with the two inlet ports being 180 degrees on center and the two exhaust ports being 180 degrees on center. Also each inlet port is spaced 90 degrees on center from each exhaust port. All of the ports are of substantially the same length and size and, when

rotated, are adapted to communicate with the same cylindrical area. Using the configuration shown, a complete hammer cycle occurs every 180 degrees of rotation of the valve.

As to the upper and lower passages in the hammer, note that upper or first hammer passages 27 and lower or second hammer passages 29 reciprocate up and down with hammer 17, as far as the operation of the percussive unit is concerned, these passages do not rotate when opening and closing to the ports in the rotating valve. A hammer cycle includes one upstroke and one downstroke per every 180 degrees of rotation of the tubular valve.

A diagram representing a typical hammer cycle is shown in FIGURE 21. In this diagram, the vertical axis represents vertical movement or displacement of the hammer while the horizontal axis represents either time or angular movement of the valve. The curve of FIGURE 21, therefore, represents the relative positions of the hammer and valve during one cycle of the hammer. References to FIGURES 1 and 21 will aid in an understanding of the operation of the valve and hammer.

It should also be noted that the basic components of the percussive unit are a ported rotating valve for supplying power fluid to and removing power fluid from the ends of the hammer, a reciprocating hammer with upper and lower passages, a cam and follower, and a rebound spring above the hammer.

In the diagram, at time zero, the hammer rests on anvil 13, inlet ports 37 are just opening to lower hammer passages 29 and exhaust ports 39 are just opening to upper hammer passages 27. Power fluid enters rotary drive means 35 via insert 59 and passes outward through jet passages 51 and 53. The power fluid emits from jet openings 55 and 57 causing the rotary drive means to rotate tubular valve 31. Power fluid passes downward in passageway 45 through inlet openings 33 and into the inlet section of tubular valve 31. Power fluid inlet ports 37 communicate with lower or second hammer passages 29 which in turn communicate with the underside surfaces of the hammer. The power fluid pressure acting on the underside surfaces of the hammer causes the hammer to accelerate upward in its up or return stroke. At the same time, power fluid above the hammer is exhausted through upper first hammer passages 27, power fluid exhaust ports 39 and the exhaust section of tubular valve 31 where the exhausted fluid is conducted through anvil passage 15 to the drill bit.

Hammer 17 accelerates upward causing single-acting cam surface 81 to rise to a point where the cam surface could contact cam follower 83. Whether or not cam follower 83 contacts cam surface 81 will depend on the angular or rotative position of tubular valve 31. If the valve is rotating either too fast or too slow relative to the position of the hammer, single-acting surface 81 will contact the cam follower causing the follower to follow the cam surface thereby coordinating the axial motion and position of the hammer with the angular or circumferential rotative position of inlet ports 37 and exhaust ports 39 in the tubular valve.

Hammer 17 continues to accelerate upward in its upstroke as long as power fluid passes from inlet ports 37 to second hammer passages 29 and the underside of the hammer. At the desired moment of upward hammer travel and valve rotation, power fluid inlet ports 37 rotate out of communication with second hammer passages 29 cutting off the flow of power fluid to the underside of the hammer. In the diagram of FIGURE 21, this point in the hammer's cycle occurs when the valve has rotated angular distance or time X and the hammer has traveled upward longitudinal distance B. The exact point in the upward travel of the hammer when the valve shuts off the flow of power fluid will be adjusted to the compressibility of the power fluid, to the type of rebound cushion above the hammer and to other factors.

In the embodiment shown, at the same time as power

fluid inlet ports 37 rotate out of communication with second hammer passages 29, power fluid exhaust ports 39 rotate out of communication with first hammer passages 27; however, it should be realized that the size or shape of these ports could be varied to adjust the timing of these occurrences to suit the power fluid and other operating conditions. For example, if the power fluid were an incompressible liquid, it would be desirable to permit the fluid above the hammer to escape through power fluid exhaust ports 39 until approximately the movement that the hammer reaches its maximum upward travel as hereafter described.

When power fluid inlet ports 37 rotate out of communication with the second hammer passages, the hammer continues to travel upward decelerating and compressing springs 67 and 69 until the upward energy of the hammer is absorbed by these springs and the drill string. The upward distance traveled by the hammer during this period of deceleration is shown in the diagram of FIGURE 21 by the distance C. The peak upward distance traveled by the hammer is the distance D. Preferably, the hammer will contact the springs at the same moment as the flow of power to the underside of the hammer is cut off. Consequently, the springs are compressed by the distance C and the springs remain in contact with the hammer until the hammer travels downward a corresponding distance. During this period from the instant that the hammer contacts the springs to the moment that the hammer leaves the springs, the valve rotates the angular distance or time Y. The importance of Y will be illustrated later.

Before the hammer reaches its upward peak, tubular valve 31 rotates far enough for power fluid inlet ports 37 to communicate with upper or first hammer passages 27. High pressure power fluid passes upward via passages 27 to exert its pressure on the upside surfaces of the hammer. This pressure causes some deceleration of the hammer and, once the hammer reaches its peak upward travel, causes the hammer to accelerate downward.

For reasons hereinafter made apparent, it is important that some of the upstroke energy of the hammer be conserved and returned to the hammer when the hammer starts to accelerate downward in its power stroke. The energy returned to the hammer is stored in returnable or reusable form by the springs above the hammer.

In the embodiment shown, at the same instant as power fluid inlet ports 37 rotate into communication with first hammer passages 27, power fluid exhaust ports 39 rotate into communication with lower or second hammer passages 29. This allows fluid beneath the hammer to exhaust through second hammer passages 29 and power fluid exhaust ports 39 and into anvil bore 15.

The hammer accelerates downward until it leaves springs 67 and 69. After leaving these springs and during the period Z, the hammer accelerates downward until it impacts the anvil. The cycle then repeats itself.

It should be noted that during a major and critical portion of each hammer cycle when the hammer is changing from its upstroke to its downstroke, single-acting cam surface 81 acts as a limit or control on the position of cam follower 83 to assure that inlet ports 37 and exhaust ports 39 open and close to first and second hammer passages 27 and 29 at the optimum moment as determined by the position of the hammer.

The operation of the embodiment illustrated in FIGURE 18 is similar except that the double-acting groove cam 91 causes the valve to rotate, and except for the fact that throughout the cycle, the double-acting groove acts as a limit or control on the angular position of follower 83' relative to the position of the hammer.

There are times when the bit is off-bottom or when the anvil is below its normal operating position that it is desirable to cease reciprocation of the hammer while maintaining flow of power fluid. In the embodiments of FIGURES 1 and 18, this is accomplished by placing and

properly spacing annular bypass passage 95 around central bore 25 or 25'. During normal operation, annular bypass passage 95 is above inlet ports 37 and exhaust ports 39; however, whenever the anvil drops allowing the hammer to also drop below its normal rebound position, annular bypass passage 95 drops to a position where the bypass passage communicates with both inlet ports 37 and exhaust ports 39 at the same time. When this happens, the power fluid flows through the valve without causing the hammer to reciprocate. It should be recalled that, in the embodiment of FIGURE 18, the follower inside double-acting groove cam 91 would keep the hammer from dropping if it were not for upper groove 93.

In the diagram of FIGURE 21 and the above description of the operation of the percussive unit, a hammer displacement cycle was divided into the three distinct periods, X, Y, and Z, with the total period per cycle being T. During period X, high pressure power fluid acts on the lower surface areas of the hammer and accelerates the hammer upward a distance B. At this point, the hammer and valve are properly synchronized by the cam and follower and the pressure exerted by the power fluid is changed. At the start of period Y, the hammer contacts the springs. The hammer loses its upward energy compressing these springs until it reaches the peak of its upward stroke. The hammer reverses its direction of movement and the springs expand returning energy to the hammer until the hammer travels downward far enough to break contact with the springs. The period Y covers the period that the hammer is in contact with the springs. During this period Y, the hammer travels a distance of 2C. During the period Z, after the hammer leaves the springs, high pressure power fluid acting on the upper surface areas of the hammer accelerates the hammer downward to impact the anvil.

In a percussive earth drilling system, it is desirable that the hammer impact energy be close as practical to the energy level at which the bit can properly function and that the frequency of these high energy level impacts be as great as practical. It has been found that the frequency and energy level of the impacts is greatly affected by the characteristics of the rebound cushion above the hammer and by the timing relationship between the rotatable tubular valve and hammer. All of these operating features are closely related to the period Y and affect most of the objectives originally set forth. They especially affect the uniformity or smoothness of operation of the percussive unit which are necessary for sustained long periods of rapid drilling.

The energy for hammer impact is primarily developed during the periods X and Z when the power fluid is accelerating the hammer. If some of the upward energy developed during the period X is to be usable as impact energy, this upward energy must be turned into downward energy. In the embodiment shown, this is accomplished with the springs above the hammer during the period Y. This process of changing upward energy to downward energy many times per minute involves inherent energy losses and the problems created by cyclic stresses and by rapid repetition of compression and expansion. It has been found that these inherent energy losses and associated problems do much more than merely cause a corresponding proportional loss of energy available for use as hammer impact energy.

For example, it has been found that too low a spring coefficient, which is expressed in force per unit of compression, seriously limits the frequency of the impacts and causes an excessive loss in impact energy. If the spring coefficient is too low, the reversal period Y is too long. When the period Y increases, the sum of the periods Y and Z increases until the sum of these periods is greater than X, that is, the time required to complete the periods Y and Z is greater than one-half of the hammer cycle. When this occurs, the amount of impact energy lost by increasing the period Y increases expo-

nentially. For the embodiment illustrated above, this can best be shown by relating the periods X, Y and Z to the corresponding angular tubular valve movements. The angular period X is the angle that the valve rotates before the flow of high pressure power fluid is switched from one end of the hammer to the other end, that is, 90 degrees. In other words, everytime the valve rotates 90 degrees the flow of high pressure power fluid is switched. When the hammer takes too much time to reverse its upward movement and the period Y is too long, the sum of Y and Z is greater than the time that it takes the valve to rotate 90 degrees; consequently, the flow of high pressure power fluid is switched to the underside of the hammer before the downstroke or powerstroke of the hammer is completed. When the valve switches prematurely, the energy input during the period Z is decreased and the power fluid acts on the underside of the hammer counterbalancing downward energy in the hammer. This decelerates the hammer before impact. In fact, if the power fluid were incompressible or if the sum of Y and Z were excessively large, the hammer would never strike the anvil. Instead the hammer would lose its potential impact energy to power fluid between the hammer and anvil. In addition to causing a large loss of impact energy, premature switching of the valve causes a lengthening of the reversal time between the power stroke and upstroke of the hammer in a manner similar to the way that the period Y is increased by too low a spring coefficient. This increased reversal time causes adverse effects similar to those caused by increasing the period Y.

For the embodiment illustrated, hammer displacement and the period Y are controlled by the springs above the hammer and angular valve movement during this period by the cam and follower. As shown above, the springs coefficient, which is expressed as force per unit of compression, is important to the operation of the percussive unit and the length of the period Y. It has been found that this spring coefficient should be at least as great as 5,000 pounds per inch. The following example will show one reason why this minimum spring coefficient is required.

For the valve illustrated, the period X equals 1 and T equals 2; consequently, the sum of the periods Y and Z should be equal to or less than 1. Theoretically, the distance of acceleration up and down for the hammer during periods X and Z is the same and the sum of X and Z equals the square root of 2. The period Z, therefore, equals 0.41. The period Y equals 1.0 minus 0.41 or 0.59. As a result, theoretically, the period Y should be equal to or less than 0.59. As a practical matter, however, for compressible power fluids, the period Y may exceed 0.59 provided that the period Y is not long enough to cause an excessive decrease in the impact energy and impact frequency. For example, the period Y could be as great as 0.7 for some percussive units.

If 0.7 is used as an upper limit for the period Y, a minimum theoretical spring coefficient for the spring above the hammer may be calculated. This minimum theoretical coefficient is required to prevent Y from exceeding the upper 0.7 limit. It should be remembered that, in order to optimize the impact energy, impact frequency and percussive unit operation, the spring coefficient should be much greater than the calculated minimum because the period Y should be equal to or less than the theoretical value 0.59. Also friction and other losses in the percussive unit tend to increase the period Y. These were not taken into account in determining the minimum theoretical value for Y; consequently, an even greater spring coefficient is required.

The minimum required spring coefficient may be estimated by the following formula:

$$K = \frac{\pi^2 (PA)^2}{2Y^2 E} \quad (1)$$

where K is the spring coefficient in pounds per inch, P is

the power fluid pressure differential across the hammer, A is the area of the hammer acted upon by P, E is the upstroke hammer energy in inch-pounds and Y is the period for turn around of the hammer.

In a typical 4.25-inch O.D. percussive unit, PA is 700 pounds and E is 960 inch-pounds. When Y equals its maximum value of 0.7 and these values are substituted in Equation 1, Equation 1 reduces to

$$K = \frac{\pi^2 (700)^2}{(2)(0.7)^2 (960)} \quad (2)$$

and K equals 5,000 pounds per inch, which as stated previously, is the minimum value for K.

In a typical 4.25-inch O.D. percussive unit, PA is 700 pounds and E is 960 inch-pounds. When Y equals its maximum value of 0.7 and these values are substituted in Equation 1, Equation 1 reduces to

Preferably, for reasons noted previously, the spring coefficient should be much greater than 5,000 pounds per inch. As an example, if a value of Y equals 0.5 is used in Equation 2 instead of Y equals 0.7, the value of K is 10,000 pounds per inch.

Percussive units for deep earth borehole drilling are such that there are severe design limitations for the spring above the hammer. There is a limit on available head space above the hammer. There are also practical limitations on hammer mass, hammer travel, hammer reversal distance and time, spring efficiencies, allowable spring stresses, allowable spring energy losses, power fluid pressure differentials, hammer rebound velocity, and the like. These design limitations preclude the use of a standard coil spring. For example, when a 4.25-inch O.D. tool was constructed along the lines illustrated in FIGURES 1 and 2 and designed to provide suitable impact energy and frequency, the highest coil spring coefficient that could be obtained with a single coil spring that exhibited the necessary energy storage capacity together with fatigue resistance was less than 3,500 pounds per inch.

The improved, double helical, parallel-acting coil-type spring shown in FIGURE 1 had a spring coefficient between 9,000 and 10,000 pounds per inch as compared to a rate of less than 3,500 pounds per inch for a single coil spring, but even the double parallel coiled spring is deficient in many ways and is especially deficient when higher spring coefficients are required to improve the performance of the percussive unit. In addition to having a high spring coefficient, the spring should exhibit high energy storage per unit mass and volume. The spring displacement should be closely aligned with the axis of the hammer and the spring force should be through the center of hammer mass. The spring should also exhibit low fluid damping characteristics, that is, as the spring compresses and expands, the amount of fluid displacement per cycle should be low. Moreover, the spring should display low energy losses due to extraneous vibrations or spring surges. It was discovered that an elongated rod-like spring made of materials with high compressive yield strength that will store energy elastically and placed with the longitudinal axis of the rod parallel to longitudinal axis of the hammer possessed these properties provided that the length of the rod was at least twelve times as great as the average maximum width of the major length of the bar or rod-like member which does not need to be round. For example, a rod spring having a length of 33.25 inches and a width or rod diameter of 0.25 inch and a Young's modulus of 30 million pounds per square inch had a spring coefficient of 44,400 pounds per inch. This type of compression rod spring is illustrated in FIGURES 18 and 22 through 24, and has been described previously. When properly designed and positioned, the rod spring operates under much higher allowable stresses. The stress is all compressive and the spring material is stressed uniformly. The rod springs exhibit much higher spring coefficients and storage capacities with much less inherent energy loss than coil

springs. For example, when the hammer rebounds from the spring, the spring retains a certain amount of kinetic energy. This retained energy is lost. This lost energy is proportional to the square of the hammer velocity and the spring mass. The mass of the rod spring per unit energy is less than the mass of a coil spring required to store the same energy. In other words, inherent energy losses in the rod spring are much less than inherent energy losses in a coil spring.

From the foregoing discussion of the operation and cycle of the hammer and rotatable tubular valve, it should now be apparent that the timing and smoothness of operation of the valve affects the entire operation of the percussive unit including impact energy, impact frequency, wear of the operating parts, and the like. One problem encountered with a rotating valve is irregular speed of rotation. There are periods when the valve tends to rotate either too fast or too slow. Much of this irregular valve movement is due to friction and the pulsations in power fluid flow. Some of the friction can be overcome by providing adequate clearance between the tubular valve and hammer, that is, a clearance that prevents undue rubbing or contact due to play in the bearings; however, there were still intermittent periods of excessive friction and pulsations in the speed of rotation of the valve. It was discovered that periods of excessive drag on the rotating valve occur when the power fluid pressure distribution on the valve is unduly eccentric. For example, in a two-ported tubular valve, that is, a valve having only one power fluid exhaust port and only one power fluid inlet port, the side of the valve adjacent the power fluid inlet port is exposed to high power fluid pressure, while the side adjacent the exhaust port is exposed only to exhaust fluid pressure. A net eccentric force results which is further aggravated by play in the valve bearings. This eccentric unbalance has been eliminated by providing greater circumferential or radial symmetry to the power fluid inlet ports and the power fluid exhaust ports so as to better equalize the radial forces due to different power fluid pressures. This symmetry is accomplished by providing two power fluid inlet ports 180 degrees on center and two power fluid exhaust ports 180 degrees on center and spaced so that each exhaust port is 90 degrees on center from an inlet port. It would be possible to use a greater number of inlet and exhaust ports than two each. A large number of inlet and exhaust ports may be especially advantageous in large diameter tools operating at high pressure and frequencies.

It should be noted further that by increasing the number of ports and placing them symmetrically around the tubular valve, the frequency and conductivity to fluid flow of the percussive unit is increased. This also reduces the effect of power fluid pressure pulsations on the valve.

While the invention has been described in connection with certain specific embodiments thereof, it will now be understood that further modifications will suggest themselves to those skilled in this art and it is intended to cover such modifications as fall within the scope of the foregoing description and appended claims. For example, it should be recognized that the first and second hammer passages or the power fluid inlet and outlet valve ports may be varied in number, location and size to adapt the tool to different modifications. One such variation is shown in FIGURE 18 wherein lower or second hammer passages 29' are formed in the inside wall of the central bore through hammer 17'. A second such variation is shown in FIGURE 3 wherein the tubular valve does not extend into the anvil as it does in FIGURE 2. Instead, the upper end of anvil 13' is equipped with cylinder extension 97 which extends upward from the anvil into control bore 25' of hammer 17''. The lower end of the hammer reciprocates up and down on cylindrical extension 97 which acts as a seal for the lower end of

the hammer. This variation would be especially useful for very long liquid-driven hammers.

I claim:

- 5 1. In a power fluid operated percussive unit of a rotary percussive drilling system having a hammer means and a drilling means and wherein the percussive unit and the drilling means are rotated and the drilling means is impacted against the earth by axial cyclic reciprocation of the hammer means, an improved valving system comprising:
  - 10 (a) a tubular, rotatable valve having at least one inlet port located in said valve in a position to alternately pass power fluid to passages communicating with the opposite ends of said hammer means as said valve is rotated, and at least one outlet port located in said valve in a position to alternately pass power fluid from said passages communicating with said opposite ends of said hammer means to a power fluid exhaust passage as said valve is rotated, and
  - 15 (b) motion conversion means adapted to employ the reciprocating movement of said hammer means to coordinate the axial position of said hammer means with the circumferential rotative position of said ports in said valve during at least a portion of the reciprocating cycle of said hammer means.
- 20 2. The improved valve of claim 1 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.
- 25 3. The improved valve of claim 1 wherein the motion conversion means is a cam and follower means, said cam having at least one curved surface positioned to contact said follower during at least a portion of the reciprocating cycle of said hammer means.
- 30 4. The improved valve of claim 3 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.
- 35 5. The improved valving system of claim 3 wherein the cam is a double-acting cam having at least two curved surfaces and the follower is placed between said surfaces of said double-acting cam, said double-acting cam and said follower being adapted to employ the reciprocating movement of said hammer means to rotate said valve upon reciprocation of said hammer means and to coordinate the axial position of said hammer means with the circumferential position of said ports in said valve.
- 40 6. The improved valve of claim 5 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.
- 45 7. The improved valving system of claim 1 wherein the rotatable tubular valve is connected to rotary drive means adapted to rotate said valve relative to the hammer.
- 50 8. The improved valving system of claim 7 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.
- 55 9. The improved valving system of claim 7 wherein the motion conversion means is a cam and follower means, said cam having at least one curved surface posi-

tioned to contact said follower during at least a portion of the reciprocating cycle of said hammer.

10. The improved valving system of claim 9 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.

11. In a percussive earth drilling unit having an elongated tubular casing, a piston-like hammer having an upper surface and a lower surface, said hammer being slidably mounted in said casing and adapted to reciprocate up and down within said casing, an anvil surface slidably mounted in said casing below said hammer and positioned to be impacted by downward movement of said lower surface of said hammer when the percussive unit is in its normal drilling position, said percussive unit and casing being adapted to receive and discharge power fluid in a manner which causes said hammer to undergo a fluid actuated reciprocating upstroke and downstroke movement within said casing, a spring mounted within said casing above said upper surface of said hammer, and positioned to contact said upper surface of said hammer during a portion of said upstroke of said hammer, said spring adapted to receive energy from said hammer during the last part of said upstroke and to return a portion of said energy during the first part of said downstroke of said hammer, an improved spring comprising at least one elongated rod-like member being at least twelve times as long as it is wide with its longitudinal axis substantially parallel to the longitudinal axis of said casing, said rod-like member having a lower end positioned to contact said upper surface of said hammer and receive energy from said hammer during said last portion of said upstroke and to return a portion of said energy during said first part of said downstroke.

12. The improved spring of claim 11 wherein the vertical sides of the at least one rod-like member are supported laterally thereby preventing buckling of said rod-like member.

13. In rotary percussive earth drilling wherein a percussive unit and an earth drill are rotated and the drill is impacted against the earth by axial cyclic reciprocation of a hammer within the percussive unit, a power fluid-operated percussive unit comprising an elongated casing, an anvil surface slidably mounted in the lower end of said casing, a piston-like hammer slidably mounted for reciprocating up and down movement in said casing above said anvil surface, said hammer having an upper surface and a first hammer passage communicating with said upper surface, said hammer having a lower surface and a second hammer passage communicating with said lower surface, a rotatable tubular valve passing longitudinally through said hammer, said tubular valve having a valve inlet passage adapted to pass fluid into said valve and a valve outlet passage adapted to pass power fluid from said valve, at least one first valve port located in said valve in a position to alternately pass said power fluid from said valve inlet passage to said first hammer passage and to said second hammer passage as said valve is rotated, at least one second valve port located in said valve in a position to alternately pass said power fluid from said first and said second hammer passages to said valve outlet passage as said valve is rotated, and motion conversion means adapted to employ the reciprocating movement of said hammer to coordinate the axial position of said hammer with the circumferential rotative position of said first and said second valve ports during at least a portion of the reciprocating cycle of said hammer.

14. The percussive unit of claim 13 wherein there are at least two first valve ports and at least two second valve ports, said at least two first valve ports being spaced substantially symmetrically around the circumference of said

valve and said at least two second valve ports being spaced substantially symmetrically around the circumference of said valve and from said inlet ports.

15. The percussive unit of claim 13 wherein the motion conversion means is a cam and follower means, said cam having at least one curved surface positioned to contact said follower during at least a portion of the reciprocating cycle of said hammer means.

16. The percussive unit of claim 15 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.

17. The percussive unit of claim 15 wherein the cam is a double-acting cam having at least two curved surfaces and the follower is placed between said surfaces of said double-acting cam, said double-acting cam and said follower being adapted to employ the reciprocating movement of said hammer means to rotate said valve upon reciprocation of said hammer means and to coordinate the axial position of said hammer means with the circumferential position of said ports in said valve.

18. The percussive unit of claim 17 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.

19. The percussive unit of claim 13 wherein the rotatable tubular valve is connected to rotary drive means adapted to rotate said valve relative to the hammer means.

20. The percussive unit of claim 19 wherein the motion conversion means is a cam and follower means, said cam having at least one curved surface positioned to contact said follower during at least a portion of the reciprocating cycle of said hammer.

21. The percussive unit of claim 19 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.

22. The percussive unit of claim 21 wherein the motion conversion means is a cam and follower means, said cam having at least one curved surface positioned to contact said follower during at least a portion of the reciprocating cycle of said hammer.

23. The percussive unit of claim 13 wherein there is a spring mounted with said casing above said upper end of said hammer, said spring positioned to contact said upper surface of said hammer and receive energy from said hammer during a last part of the upward movement of said hammer and to return a portion of said energy during a first part of the downward movement of said hammer, said spring having a spring rate of at least 5,000 pounds per inch.

24. The percussive unit of claim 23 wherein the motion conversion means is a cam and follower means, said cam having at least one curved surface positioned to contact said follower during at least a portion of the reciprocating cycle of said hammer means.

25. The percussive unit of claim 24 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports.

26. The percussive unit of claim 13 wherein there is at least one elongated rod-like spring member mounted within said casing above said upper end of said hammer,

said spring member being at least twelve times as long as it is wide with its longitudinal axis substantially parallel to the longitudinal axis of said casing, said rod-like member having a lower end positioned to contact said upper surface of said hammer and receive energy from said hammer during a last part of the upward movement of said hammer and to return a portion of said energy during a first part of the downward movement of said hammer.

27. The percussive unit of claim 26 wherein the motion conversion means is a cam and follower means, said cam having at least one curved surface positioned to contact said follower during at least a portion of the reciprocating cycle of said hammer means. 10

28. The percussive unit of claim 27 wherein there are at least two inlet ports and at least two exhaust ports, said at least two inlet ports being spaced substantially symmetrically around the circumference of said valve and said at least two exhaust ports being spaced substantially symmetrically around the circumference of said valve and from said inlet ports. 15 20

29. The percussive unit of claim 13 wherein said valve inlet passage inside said tubular valve has a contaminant removal means, said contaminant removal means adapted to collect contaminants moving along the walls of said valve inlet passage and to discharge said contaminants directly to said valve outlet passage inside said tubular valve. 5
